George R. Lippitt, Cleveland Heights, Ohio, assignor to Eaton Manufacturing Company, Cleveland, Ohio, a corporation of Ohio

Application March 22, 1939, Serial No. 83,763

Term of patent 7 years

To all whom it may concern:

Be it known that I, George R. Lippitt, a citizen of the United States, residing in Cleveland Heights, in the county of Cuyahoga, State of Ohio, have invented a new, original, and ornamental Design for a Vehicle Heater, of which the following is a specification, reference being had to the accompanying drawing, forming a part thereof, wherein:

Figure 1 is a perspective view of a vehicle heater embodying my new design.

Fig. 2 is a bottom plan view of the heater shown in the perspective of Fig. 1.

Fig. 3 is a side elevational view of the heater shown in Fig. 1.

Another view of the side elevation of the heater opposite that from Fig. 3 would be identical.

The rear wall of the heater opposite that of front wire mesh screen in Fig. 1 would be similar only smaller in height, as shown by the side of Fig. 1.

What I claim is:

The ornamental design for a vehicle heater, substantially as shown and described.

GEORGE R. LIPPITT.
